(57) **CLAIM**

The ornamental design for a beverage container lid, as shown and described.

DESCRIPTION

FIG. 1 is a top perspective view of a lid for a cup showing the novel lid design.

FIG. 2 is a front side view, taken looking at the front of the lid design.

FIG. 3 is a back side view, taken looking at the back of the lid design.

FIG. 4 is a left side view, taken looking at the left side of the lid design.

FIG. 5 is a right side view, taken looking at the right side of the lid design.

FIG. 6 is a top plan view taken looking down at the top of the lid design.

FIG. 7 is a bottom plan view taken looking up at the underside of the lid design; and,

FIG. 8 is a bottom perspective view of a lid for a cup, looking up at underside of the novel lid design.

In each of the drawing figures, surface shading is used to clearly show the character and contour of all surfaces of the 3-dimensional aspects of the design, and form a part of the design sought to be protected.
